US00D778954S

(12) United States Design Patent (10) Patent No.: US D778,954 S
Sun (45) Date of Patent: * Feb. 14, 2017

(54) DISPLAY SCREEN OR PORTION THEREOF WITH ICON

(71) Applicant: Samsung Electronics Co., Ltd., Suwon-si, Gyeonggi-do (KR)

(72) Inventor: Youngpil Sun, Seongnam-si (KR)

(73) Assignee: SAMSUNG ELECTRONICS CO., LTD., Gyeonggi-Do (KR)

() Term: 15 Years

(21) Appl. No.: 29/546,962

(22) Filed: Nov. 30, 2015

(30) Foreign Application Priority Data

Sep. 25, 2015 (KR) 30-2015-0048994

(51) LOC (10) Cl. 14-04

(52) U.S. Cl.

USPC D14/492

(58) Field of Classification Search

USPC D14/485-495

CPC . G06F 3/04817; G06F 3/0481; H04N 1/00424

CLAIM

I claim, the ornamental design for a display screen or portion thereof with icon, as shown and described.

DESCRIPTION

The FIGURE is a front view of a display screen or portion thereof with icon, showing my new design.

The broken line illustrates a portion of the display screen and forms no part of the claimed design.

1 Claim, 1 Drawing Sheet
